UNITED STATES PATENT OFFICE

EDWARD W. STEVENS, OF DETROIT, MICHIGAN, ASSIGNOR TO CHICAGO PNEUMATIC TOOL COMPANY, OF NEW YORK, N. Y., A CORPORATION OF NEW JERSEY

FLUID PRESSURE TOOL

Application filed May 16, 1930. Serial No. 452,827.

This invention relates to percussive tools operated by fluid pressure such as compressed air and more particularly to light weight rock drills of the type having a valve for controlling the distribution of the motive fluid.

Among the objects of the invention are to develop a simplified construction for such tools with a very compact valve housing, to reduce the number of valve parts to a minimum, to avoid sharp bends in the supply passages which lead to the ends of the piston chamber, to reduce the cost of manufacture and the expense of up-keep, and in general to improve prior devices in respect to efficiency and service.

In order to illustrate the invention one concrete embodiment thereof is shown in the accompanying drawing in which:

Fig. 1 is a longitudinal sectional view showing the hammer piston beginning its downward or power stroke;

Fig. 2 is a sectional view similar to Fig. 1 showing the piston beginning its rearward or non-working stroke;

Fig. 3 is a detail sectional view substantially on the line 3—3 of Fig. 2; and

Fig. 4 is a sectional view similar to Fig. 3 showing a modification in the porting arrangement.

The embodiment of the invention chosen for the purpose of illustration comprises an automatic rotation rock drill which is conventional as to most of its features. The drill comprises a cylinder 5 within which reciprocates a hammer piston 6 controlling main exhaust ports 7 and 8 and adapted to impart blows directly to a drill steel 9 supported in a rotary chuck 10 mounted in a front head 11 secured to cylinder 5. The opposite end of the cylinder is closed by cylinder ring 12 and handle 13 which together support the rifle bar 14 which cooperates with rifle nut 15 in piston 6 to impart rotation to cylinder 5, which rotary impulse is transmitted by the piston to chuck 10 by the usual splined connection.

Cylinder 5 has at one side an externally projecting boss 16 which is preferable integral with the cylinder. The boss is generally cylindrical in shape as indicated in Figs.

3 and 4 and provides opposed arcuate valve seats. In the peripheral surface of these valve seats are ports 17 and 18 from which extend substantially straight but downwardly inclined passages 17a and 18a opening into the piston chamber at the opposite ends thereof by ports 17b and 18b.

A cap 19 encloses boss 16 to provide a valve chamber therearound and is secured to cylinder 5 by any suitable means such as cap screws 20 extending through lugs 19a on member 19. Within the valve chamber thus provided and encircling boss 16 for alternate engagement with the valve seats on the same to control the ports 17 and 18, is a ring valve 21 which slidably engages the base of boss 16 on the one hand and the interior of cap 19 on the other. Cap 19 has a threaded bore 19b to which the motive fluid inlet conduit (not shown) is secured with the result that the pressure fluid is admitted to the valve chamber within valve 21. The clearance between boss 16 and cap 19 about inlet 19b is restricted, as clearly shown in Figs. 1 and 2, for a purpose presently to be described.

As indicated in Fig. 3, the shape of boss 16 is such that, when valve 21 engages one of the valve seats, it leaves an elliptically shaped area through which the motive fluid may pass freely across the other seat to the then open port, in the present instance port 17, and a similar situation obtains when the valve is in its opposite position. In order to get a freely acting valve, means are provided for utilizing a portion of the live motive fluid to assist in breaking the seal over either port 17 or port 18 when closed by valve 21. For this purpose balancing reliefs are provided in the valve seats on both sides of ports 17 and 18. One way of making these reliefs is to grind flats as indicated at 16a on the boss 16.

The operation of the hammer will be apparent to those skilled in the art and may be briefly stated as follows: With the parts in the position shown in Fig. 1 live motive fluid from inlet 19b is passing through the elliptical area at the left of boss 16 through port 18, passage 18a, and port 18b into the rear end of the piston chamber to drive piston 6 on its forward or working stroke. Ports

17b, passage 17a, and port 17 are vented to atmosphere through main piston controlled exhaust port 8 and port 17 is sealed off from the inlet by valve 21. As the piston moves forward to strike its blow, it seals main exhaust 8 but uncovers main exhaust 7 with the result that the pressure is relieved in the rear end of the piston chamber as well as in passage 18a and, due to the restriction provided between boss 16 and cap 19 which limits the amount of motive fluid passing to port 18, there is a distinct drop in pressure on the internal surface of the valve at this point. At the same time the air trapped and compressed in front of piston 6 is forced through port 17b, passage 17a, and port 17 against the internal surface of the valve over port 17, which pressure is assisted by live motive fluid from the inlet port bearing on the internal surface of the right side of the valve through reliefs 16a on either side of ports 17. Accordingly, the valve is thrown to the position shown in Figs. 2 and 3 thereby sealing port 18 and uncovering port 17, thus admitting the live motive fluid through passage 17a and port 17b to the front end of the piston chamber to drive piston 6 rearwardly. As the piston seals main exhaust port 7 and uncovers main exhaust port 8, the pressure obtaining on the opposite sides of valve 21 are reversed and the valve is thrown to the original position shown in Fig. 1.

In the modification shown in Fig. 4 the porting arrangement is such that the inlet ports to the piston chamber, 18z and 17z, are on the same centre axial line instead of at opposite sides of such a line as in Fig. 3. To produce this effect without lengthening the passages or making undesirable bends in the same, the seats engaged by valve 21 are displaced about 30° from the position shown in Fig. 3 so that the valve moves angularly of cylinder 5 rather than axially. With this arrangement the cross passages 18y and 17y, which connect the valve controlled ports 18z and 17z with the piston chamber ports 18z and 17z, are at an angle to the axis of the cylinder as well as at a downward inclination. By using plain ports at 17z and 18z rather than the undercut arcuate ports shown in Figs. 1, 2, and 3, relief areas 16z of greater extent are possible than in the form first described. Such larger reliefs make the valve more sensitive to changes in pressure.

From the above it will be apparent that the present invention is characterized by a minimum number of very simple valve parts. Moreover the throttling of the incoming fluid by the close approach of cap 19 to valve boss 16 and the use of balancing reliefs on the valve seats permit an extremely sensitive control of the movement of the valve. The construction also provides for passages to the piston chamber under control of the valve

which are straight and direct and without sharp bends by crossing the same through the boss which provides the valve seats.

While the invention has been herein disclosed in what are now considered to be preferred arrangements, it is to be understood that the invention is not limited to the specific details thereof but covers all changes, modifications, and adaptations within the scope of the appended claims.

I claim as my invention:

1. In a fluid pressure percussive tool, a cylinder having a boss on the side thereof, a cap extending over said boss to provide a valve chamber therearound, a ring valve encircling said boss and slidably engaging the base of the same and the interior of said cap, said boss having ports in the peripheral surface thereof for control by said valve with passages leading therefrom to the opposite ends of said cylinder, and means for admitting motive fluid to said valve chamber.

2. In a fluid pressure percussive tool, a cylinder having a boss on the side thereof, ports in the opposite sides of said boss and cross passages leading straight from said ports to the opposite ends of said cylinder, a cap extending over said boss to provide a valve chamber therearound, a ring valve encircling said boss and movable transversely thereof to control said ports in alternation, and means for admitting motive fluid to said valve chamber.

3. In a fluid pressure percussive tool, a cylinder having a boss on the side thereof providing opposed arcuate valve seats, a port in each valve seat, cross passages leading from said ports straight to the opposite ends of said cylinder, inlet means for motive fluid encircling said boss to provide a valve chamber, a ring valve encircling said boss and movable thereon to control said ports in alternation, said boss having portions of its seats cut away to provide relief areas for utilizing live motive fluid to assist in shifting the valve.

4. In a fluid pressure percussive tool, a cylinder having a boss on the side thereof providing opposed arcuate valve seats, a port in each valve seat, cross passages leading from said ports straight to the opposite ends of said cylinder, an inlet member for motive fluid encircling said boss to provide a valve chamber, a ring valve encircling said boss and movable thereon to control said ports in alternation, said boss having portions of its seats cut away to provide balancing relief areas on both sides of each of said ports.

5. In a fluid pressure percussive tool, a cylinder having a boss on the side thereof, ports in the opposite sides of said boss, angularly disposed cross passages leading straight from said ports to the opposite ends of said cylinder and opening into the latter on the same axial center line, inlet means for motive

fluid encircling said boss to provide a valve chamber therearound, and a ring valve encircling said boss and movable thereon to control said ports in alternation.

5 6. A fluid pressure percussive tool comprising a cylinder, a hammer piston reciprocable therein, said cylinder having a cylindrical boss projecting from the side thereof with ports and passages leading to the opposite 10 ends of the piston chamber, means enclosing said boss to provide a valve chamber, a ring valve encircling said boss and slidably engaging with its opposite edges the base of the boss and said means respectively, said 15 valve being movable relative to said boss to control said ports in alternation and to distribute motive fluid to the piston chamber, said enclosing means admitting motive fluid to the interior of said valve and cooperating 20 with said boss to restrict the quantity passing to said ports.

7. A fluid pressure percussive tool comprising a cylinder, a hammer piston reciprocable therein, said cylinder having a cylindrical boss projecting from the side thereof with ports and passages leading to the opposite ends of the piston chamber, a member inclosing said boss to provide a valve chamber therearound, a ring valve encircling said boss 25 and movable relative thereto to control said ports in alternation, means for admitting motive fluid to the interior of said valve, said member and said boss cooperating to limit the quantity of motive fluid passing to one 30 of said valve controlled ports.

8. A fluid pressure percussive tool comprising a cylinder, a hammer piston reciprocable therein, said cylinder having a cylindrical boss projecting from the side thereof with 40 ports and passages leading to the opposite ends of the piston chamber, a member inclosing said boss to provide a valve chamber therearound, a ring valve encircling said boss and movable relative thereto to control 45 said ports in alternation, said member providing an inlet for motive fluid, and means adjacent said inlet for effecting a restriction in the quantity of motive fluid controlled by said valve.

50 9. A fluid pressure percussive tool comprising a cylinder, a hammer piston reciprocable therein, said cylinder having a cylindrical boss projecting from the side thereof with ports and passages leading to the opposite 55 ends of the piston chamber, an imperforate ring valve movably mounted on said boss to control said ports in alternation, and a motive fluid inlet member secured to said cylinder, said valve cooperating with said member to confine the admitted motive fluid to the interior of said valve.

60 10. A fluid pressure percussive tool comprising a cylinder, a hammer piston reciprocable therein, said cylinder having a cylindrical boss projecting from the side thereof with 65

ports and passages leading to the opposite ends of the piston chamber, a ring valve movably mounted upon said boss to control said ports in alternation, a motive fluid inlet member inclosing said valve and having a portion only slightly spaced from said boss to restrict the motive fluid flow thereover.

Signed by me at Detroit, in the county of Wayne and State of Michigan, this 14th day of May, 1930.
